[57] CLAIM

The ornamental design for a luminaire, as shown and
described.

DESCRIPTION

FIG. 1 is a perspective view of a luminaire showing my
new design;

FIG. 2 is a top view thereof;

FIG. 3 is a bottom view thereof; and

FIG. 4 is a cross-sectional view of the luminaire show-
ing my new design, viewed along the line 4—4 of FIG.
2, with the outer strings of the luminaire removed for
ease of illustration.

FIG. 1.FIG. 2.FIG. 4.

FIG. 3.
